UNITED STATES PATENT OFFICE.

CHARLES H. SMOOT, OF NEW YORK, N. Y., ASSIGNOR TO SLAG STEAM GENERATOR COMPANY, OF NEW YORK, N. Y., A CORPORATION OF DELAWARE.

SLAG STEAM-GENERATOR.

1,127,690.

Specification of Letter Patent.

Patented Feb. 9, 1915.

Application filed July 6, 1914. Serial No. 849,101.

To all whom it may concern:

Be it known that I, CHARLES H. SMOOT, a citizen of the United States, (whose post-office address is 90 West street, New York city and State,) have invented certain new and useful Improvements in Slag Steam-Generators, which improvements are fully set forth in the following specification.

This invention has for its object improved means by which slag or any pre-heated material can be employed to heat a liquid, which liquid, after having absorbed heat previously contained in the slag, is evaporated, the evaporation being due to a reduction of pressure on the liquid.

By means of my invention a power generating apparatus interposed between the apparatus where evaporation takes place and a condensing apparatus is supplied with motive fluid. The steam generated by the heat contained in the slag and transferred to the liquid can be used for a different purpose than to generate power, such as heating, for instance.

By means of my improved apparatus I can discharge slag into the liquid contained in an open vessel in such a manner that the temperature of the liquid will be higher than heretofore has been possible in employing known methods in which slag and water were mixed in an open vessel.

I do not wish to be limited to the specific use which can be made of the steam generated by the use of the apparatus disclosed in this specification.

The accompanying drawing is a vertical cross section of an embodiment of my invention.

A is an open vessel in which liquid is circulated by means of pipe B. Slag is discharged into vessel A from furnace C by duct D.

E is a duct which carries the slag and liquid mixed into water collecting and slag settling chamber F. In chamber F the slag falls by gravity into channel H and is carried out by conveyer I, which conveyer I in the embodiment of my invention is shown as a helical conveyer. It is obvious that any type of conveyer can be used and that I do not wish to be restricted to this special type

of conveyer. The conveyer I is driven by electric motor 2 and by means of gears 3 and 4.

5 is the discharge opening of the conveyer I.

K is an evaporating chamber, L being the duct through which the steam is discharged from said evaporating chamber K.

M is a pump which carries water contained in evaporating chamber K through pipe B into vessel A.

O is a conical shaped nozzle, which obliges the liquid carried by pipe B to flow downward through opening 23 into vessel A.

The slag discharged by duct D falling into the liquid carried by pipe B through the circular orifice 23 encounters water at high velocity in throat 8 of chamber A. The walls of the throat are formed by the exterior wall 10 of chamber A and by plates 9 and 12 hinged at point 11.

Screw 13 presses on point 11 and its displacement therefore controls the size of throat 8.

Plate 9 is allowed to slide up and down, due to its being held in place by pin 15 entering into slot 14.

16 and 17 are screws which enter nuts 18 and 19. These nuts are held to the conical shaped nozzle O and control its upward or downward motion.

By means of screws 16 and 17 the orifice of discharge of the liquid can be varied, thus giving a varying quantity for the flow of liquid down throat 8 of chamber A.

P is a pipe located on water collecting and slag settling chamber F and Q is a valve controlling the opening of pipe P.

R is a valve controlled by float S, valve R controlling the opening and closing of pipe T through which additional of make up liquid is introduced into mixing chamber A through pipe B.

U is a float controlling the opening and closing of butterfly valve V in duct L.

W is a guide for the liquid flowing from water collecting and slag settling chamber F into evaporating chamber K through pipe Y.

X is an elbow in pipe E which allows steam generated in pipe E to be discharged into the liquid contained in settling cham-

ber F through pipe Z perforated by holes 20, 20, 20.

Dotted lines and arrows 24, 25 show the difference of level or static head in chamber A as compared with liquid level in settling chamber F. Obviously, this static head can be made as great as desired.

In practising my invention, the slag falling from duct D is given an increased velocity after it mixes with the flow of liquid in chamber A. This increase of velocity is obtained by imparting velocity to the liquid carried by pipe B and discharged through orifice 23, said velocity being in turn imparted to the slag in the throat or restricted orifice 8. Through throat 8 both slag and liquid are carried downward.

The distance 24, 25 represents a static head of liquid in chamber A, into which the mixture of liquid and hot slag progresses. The presence of this static head permits the liquid to be heated to a higher temperature without evolution of steam than if it were subjected to atmospheric pressure only. The velocity of the mixture in a downward direction of throat 8 is also converted into pressure by reduction of velocity, still further increasing the head, and therefore the boiling point of the liquid, permitting a still further increase in temperature of the liquid without evolution of steam. Furthermore, the downward velocity of the mixture is sufficient to prevent the free escape of any steam which may be generated, the downward velocity of the mixture being opposed to the upward passage of steam.

For the conversion of velocity into pressure, I prefer the channel in chamber A to be divergent from throat 8 downward, although this is not necessary, and a straight channel will suffice, provided its sectional area is sufficient to permit the velocity of the mixture to be appreciably lower than the velocity of the liquid jet directed into throat 8 of chamber A.

The distance 24, 25 measures a head opposed to the pressure in water collecting and slag settling chamber F. This static head is also augmented by the velocity head or pressure produced by the reduction of velocity in that part of chamber A below throat 8.

The mixture of slag and liquid is carried through pipe E and discharged into settling chamber F. The steam entrained is allowed a passage through elbow X, which elbow X is connected with pipe B, pipe B being perforated by openings 20, 20, 20. This liberation of steam from the mixture of slag and liquid before it is discharged into settling chamber F is desirable, as it affords means to distribute the steam in the entire mass of liquid contained in settling chamber F, thus having a tendency to equalize

the temperature of said mass of liquid. The pressure in this steam space is regulated by means of a relief valve Q, allowing steam to escape from the steam space through pipe P. In steam space of chamber F the 70 gases which may be entrained or generated by the slag and liquid mixture flowing through pipe E accumulate, and when valve Q opens this accumulation of gases is liberated. The predetermined pressure applied to valve Q must be less than the static head 24, 25, plus the velocity head created by the jet of liquid flowing through throat 8 of the mixing chamber A. The slag falling by gravity through the bottom of water 80 collecting and slag settling chamber F is carried through channel H by conveyer I. The liquid is then conveyed from water collecting and slag settling chamber F into evaporating chamber K through pipe Y. 85 The guide W then brings this liquid to the upper part of the evaporating chamber K, thus giving the heated water a small static head at its point of evaporation. Steam is generated in evaporating chamber K, due 90 to diminution of pressure on the liquid. In evaporating the liquid cools and after being cooled in chamber K it is taken out by pump M and brought by pipe B through opening 23 into the mixing chamber A. Additional liquid is introduced at any suitable point, such as point 40 in the current of liquid pumped from evaporating chamber K into mixing chamber A, thus reducing as 95 much as practical the temperature of the liquid at its point of mixture with the slag. The source of additional fluid is shown diagrammatically, 36, T being a pipe for liquid flowing from 36 to point 40. Steam is carried out of the evaporating chamber K by 100 duct L until the liquid level in evaporating chamber K reaches a predetermined maximum height; float U is then brought into play and acts upon butterfly valve V by means of rod 30. The pressure limit in 105 evaporating chamber K is maintained by means of a valved opening 33; 34 being the seat and 35 the loading spring of the valved opening 33. Spring 35 will be in tension 110 or compression depending on the pressure limit in evaporating chamber being under or above atmosphere.

In the water collecting and slag settling chamber F, I use a float S controlling valve R, which allows additional or make up water from source 36 to be introduced into mixing chamber A through pipe B when float S falls under a predetermined level. The steam generated in evaporating chamber K is brought through pipe L to any suitable device creating a drop in pressure. I have shown diagrammatically a power generating apparatus, 31, connected to a condensing apparatus, 32.

I do not wish to be limited to a power gen-

erating apparatus and condensing apparatus as means to use the steam generated in evaporating chamber K.

Many other uses familiar to those skilled in the art are obvious.

It is also to be noted that the pressure of the steam discharged in evaporating chamber K may be discharged at pressures in excess of atmospheric pressure absolute.

10 In the following claims I do not wish to be restricted to slag, but to any pre-heated material which may be mixed with the liquid referred to herein.

Having thus described my invention, what I claim is:

1. A slag steam generator comprising a mixing chamber for a flow of slag and a flow of liquid and means to produce a liquid seal controlled by the flow of liquid to oppose the escape of steam from the mixture of slag and liquid.

2. A slag steam generator comprising a mixing chamber for a flow of slag and a flow of liquid having a restricted opening or throat through which the flow of slag and liquid enter said mixing chamber.

3. A slag steam generator comprising a mixing chamber for the slag and liquid having a restricted opening or throat through which the slag and the liquid enter said mixing chamber and having an enlargement of cross sectional area for the passage of the mixture of slag and liquid after it has passed through the restricted opening or throat.

4. A slag steam generator comprising a mixing chamber for the slag and liquid, having a throat or restricted opening prolonged by a diverging channel for the passage of the mixture of slag and liquid.

5. A slag steam generator comprising a mixing chamber for the slag and liquid, means to impart velocity to the liquid and means to transfer said velocity to the slag during the process of mixing.

6. A slag steam generator comprising a mixing chamber for the slag and liquid, means to impart velocity to the mixture and means to transform said velocity into pressure.

7. A slag steam generator comprising a mixing chamber for slag and liquid and means for maintaining the liquid below its boiling point and means for removing air or gas before delivering the liquid to a container closed to the atmosphere, from which steam may be generated.

8. A slag steam generator comprising a mixing chamber for slag and a liquid, means to impart velocity to the liquid and adjustable means to control the volume and the velocity of the liquid when entering into contact with the slag.

9. A slag steam generator comprising a mixing chamber for slag and a liquid, and

adjustable means controlling the velocity of the liquid when entering into contact with the slag.

10. A slag steam generator comprising a mixing chamber for slag and a liquid having a restricted and thereafter enlarged channel for the flow of the mixture of slag and liquid.

11. A slag steam generator comprising a chamber for the mixture of slag and liquid having downward converging walls forming a throat or restricted passage for the flow of said mixture and having a liquid inlet located above said throat.

12. A slag steam generator comprising a chamber for the mixture of a flow of slag and a flow of liquid, means to accelerate the velocity of the flow of said mixture at a given point of said chamber and means to reduce said velocity at a lower point of said chamber.

13. A slag steam generator comprising a mixing chamber for the slag and the liquid, a chamber for collecting the heated liquid, means to separate the slag from the liquid and means to subject the liquid contained in the latter chamber to pressures in excess of atmospheric pressure absolute.

14. A slag steam generator comprising a mixing chamber for the slag and the liquid, a chamber for collecting the heated liquid, means to separate the slag from the liquid and means to subject the liquid contained in the latter chamber to a static head of liquid.

15. A slag steam generator comprising a mixing chamber for the slag and the liquid, a chamber for collecting the heated liquid, means to separate the slag from the liquid and means to subject the liquid contained in the latter chamber to a static head of liquid and to an additional increase of pressure due to transformation of velocity of flow of mixture of slag and liquid into pressure.

16. A slag steam generator comprising a mixing chamber for the slag and the liquid, a chamber for collecting the heated liquid, means to separate the slag from the liquid and means to subject the liquid contained in the latter chamber to the pressure due to transformation of velocity of flow of mixture of slag and liquid into pressure.

17. A slag steam generator comprising a mixing chamber for the slag and liquid, a collecting chamber for the heated liquid and an evaporating chamber, all three chambers being in direct communication as concerns the liquid flow.

18. A slag steam generator comprising a mixing chamber for the slag and liquid and a collecting chamber for the heated liquid, the level of the heated liquid in the mixing chamber being maintained higher than the liquid level in the collecting chamber.

19. A slag steam generator comprising a

- 4
- mixing chamber for the slag and liquid, a chamber for collecting the heated liquid, an evaporating chamber for cooling the liquid and pumping means for circulating the 5 cooled liquid into the mixing chamber.
20. A slag steam generator comprising a mixing chamber for the slag and liquid, a chamber for collecting the heated water and means to separate in the collecting chamber 10 the gases entrained or generated in the mixture of slag and liquid.
21. A slag steam generator comprising a mixing chamber for the slag and liquid, a chamber for collecting the heated water and 15 means to separate in the collecting chamber and discharge to atmosphere the gases entrained or generated in the mixture of slag and liquid.
22. A slag steam generator comprising a 20 mixing chamber for the slag and liquid, a chamber for collecting the heated liquid and means controlled by the liquid level in the collecting chamber adapted to introduce additional liquid into the mixing chamber.
25. 23. A slag steam generator comprising a mixing chamber for the slag and liquid, a chamber for collecting the heated liquid and means to discharge in divided streams the steam generated by the mixture of slag and 30 liquid into the body of heated water contained in the collecting chamber.
24. A slag steam generator comprising a mixing chamber for the slag and liquid, a collecting chamber having direct communication with the mixing chamber for the 35 heated liquid, said collecting chamber being equipped with a valved opening, means to force the heated liquid into the collecting chamber and evaporating chamber for cooling the heated liquid.
40. 25. A slag steam generator comprising a mixing chamber for the slag and liquid, a collecting chamber for the heated liquid, equipped with a valve loaded to a maximum 45 predetermined pressure, an evaporating chamber and means to control the pressure allowable in said evaporating chamber.
26. A slag steam generator comprising a mixing chamber for the slag and liquid, a 50 collecting chamber for the heated liquid and means to separate the steam generated in the mixture of the liquid and slag before said mixture enters the collecting chamber.
55. 27. A slag steam generator comprising a mixing chamber for a flow of slag and a flow of liquid, means to increase the velocity of the flow of said mixture of slag and liquid, a collecting chamber for the heated liquid and means to separate the slag and 60 the liquid.
28. A slag steam generator comprising a mixing chamber for the mixture of a flow of slag and a flow of liquid, means to impart velocity to the slag during the process of mixing and an evaporating chamber adapted to receive the heated water and to cool same. 65
29. A slag steam generator comprising a mixing chamber for the mixture of a flow of slag and a flow of liquid, means to transform the velocity of the mixture into pressure and pumping means adapted to create a flow of the liquid. 70
30. A slag steam generator comprising a mixing chamber for the mixture of slag and 75 liquid, an evaporating chamber to cool the heated liquid and means responsive to the pressure of the steam in the evaporating chamber controlling the discharge of steam to atmosphere. 80
31. A slag steam generator comprising means to mix slag and liquid, means to collect the heated liquid under pressure in excess of atmospheric pressure and means to cool the liquid thus collected. 85
32. A slag steam generator comprising means to mix slag and liquid, means to collect the heated liquid under pressure in excess of atmospheric pressure and means to evaporate the liquid thus collected at pressures equal to or lower than atmospheric pressure. 90
33. A slag steam generator comprising means to mix slag and a liquid, means to collect the heated liquid under pressure in excess of atmospheric pressure, means to cool the liquid thus collected and means to return said cooled liquid into the mixing means for the slag and liquid. 95
34. A slag steam generator comprising means to mix slag and liquid and means to separate the liquid from the slag under pressure in excess of atmospheric pressure and means to evaporate said liquid at pressures equal to or lower than atmospheric pressure. 100
35. A slag steam generator comprising means to subject a flow of liquid to the heating action of a flow of slag, means to convert the velocity of the flow of liquid into pressure, means to collect said liquid under pressure, means to cool said liquid and means to subject the cooled liquid to the heating action of the slag. 105
- In witness whereof I hereunto subscribe my name this 3rd day of July, 1914.
